Primary Examiner — Kevin Rudzinski*(74) Attorney, Agent, or Firm* — Theodore C. Huff(57) **CLAIM**

The ornamental design for a lighting system bracket, as shown and described.

DESCRIPTION

FIG. 1 is a perspective view of a lighting system bracket showing the new design.

FIG. 2 is a front view thereof.

FIG. 3 is a back view thereof.

FIG. 4 is a top view thereof.

FIG. 5 is a bottom view thereof.

FIG. 6 is a right side view thereof; and,

FIG. 7 is a left side view thereof.

The lighting system bracket is shown with portions broken away in FIGS. 1, 4, 5, 6 and 7 to indicate the design has no specific length.
